UNITED STATES PATENT OFFICE.

HOWARD B. JERNEE, OF PERTH AMBOY, NEW JERSEY.

METHOD OF AND APPARATUS FOR BESSEMERIZING COPPER MATTE.

1,059,367.

Specification of Letters Patent.

Patented Apr. 22, 1913.

Application filed May 8, 1912. Serial No. 695,871.

To all whom it may concern:

Be it known that I, HOWARD B. JERNEE, a citizen of the United States, residing at Perth Amboy, in the county of Middlesex 5 and State of New Jersey, have invented certain new and useful Improvements in Methods of and Apparatus for Bessemerizing Copper Matte, of which the following is a specification.

10 This invention relates to apparatus for bessemerizing copper matte.

In the customary practice, the matte is treated in a converter having a silicious lining which unites with the iron present to 15 form a slag, and which lining must be frequently renewed. Many attempts to employ a magnesite, chrome-oxid or other non-corrodible lining have failed because of the practice of forcing air into the metal by the 20 use of twyters, made of metal or other material. The causes of these failures are as follows: 1. The lining around the twyters is disintegrated first. 2. The twyters, which are usually made of metal, are attacked by 25 the slag and in a short time are eaten away, necessitating the relining of the converter in the vicinity of the twyters and the renewal of the twyters. 3. The air in passing through the twyters chills the adjacent portions 30 of the metal which clogs the twyters, requiring the twyters to be continually punched to keep them open. 4. The lining shifts from the effects of the heat, causing the twyters to break or the lining to crack, 35 with resultant early disintegration. 5. If the air pressure should become low, the metal flows into the twyters and hardens, forming a solid mass which cannot be punched out, requiring removal of the clogged twyters and 40 the substitution of new ones.

The object of the present invention is to provide a method and apparatus whereby these objections are avoided, whereby a non-corrodible lining may be used with great 45 advantage and efficiency and the use of twyters dispensed with, and whereby economy of time and labor is secured and the cost of maintaining the converter in efficient working condition considerably reduced.

50 In the accompanying drawings I have shown one form of converter designed for carrying my invention into practical effect, and in these drawings: Figure 1 is a view showing the converter partially in side elevation and partially in longitudinal section. Fig. 2 is a vertical transverse section of the

same on the line 2—2 of Fig. 1. Fig. 3 is a top plan view of the converter. Fig. 4 is a vertical transverse section of the same on the line 4—4 of Fig. 3.

60 In the practice of my invention, I preferably employ a converter A, consisting of a cylindrical body or shell, rotatably sustained in any suitable manner in a horizontal position for axial movement to a requisite extent, so as to permit proper delivery of the molten matte and ready discharge of accumulated slags, white metal or blister copper. The converter is provided with a non-corrodible lining 1, of magnesite brick or 70 other suitable material, a lateral discharge spout 2, and a central opening 3 at its top for the introduction of the charge and discharge of the gases evolved in the bessemerizing action.

75 At each end of the top of the converter vessel is formed a vertical air passage 4, communicating at its upper end with a wind box or air inlet 5 and at its lower end with the interior of the converter chamber 6. 80 Branch pipes 7 connect these wind-boxes or air inlets with an air supply pipe 8 leading from a blower or compressor, whereby blasts of air are supplied in bessemerizing the metal. As shown, the central portion of the 85 top of the vessel rises above the plane of the ends thereof, the opening 3 thus being arranged above the level of the air inlets. A well or space 9 is provided in the top wall of the lining immediately below the opening 3, 90 which well or space communicates at its top with said opening and at its bottom with the center of the converter chamber. When the converter is charged the matte fills the converter chamber, air passages and well up to 95 the normal maximum level indicated by the line α — α in Fig. 1.

The bottom surfaces 10 of the outer ends of the top wall of the lining 1 are preferably straight or flat and extend well down 100 toward the bottom wall of the lining, thus contracting the ends 11 of the converter chamber 6, as shown, and the air passages 4 extend down through said end portions of the top wall and communicate with such 105 contracted ends of the chamber. From these contracted ends of the chamber the portions of the top wall of the lining between the same and the well 9 slope or incline on convergent lines upwardly at a suitable angle, 110 thus making the central portion of the top of the converter substantially dome-shaped

and providing baffles or deflectors 12 which lie in surface contact with the metal. These baffles or deflectors 12 may extend on straight or curved lines, but are preferably jogged or stepped, as shown, so that each will present a series of deflecting surfaces to increase its efficiency. I, however, do not wish to be restricted to any particular shape or arrangement of the baffles, as other forms and constructions of baffles may be employed with equal efficiency or found preferable under some conditions.

In operation, the converter chamber 6 is filled through the opening 3 with molten matte up to the indicated level and air is introduced at both ends of the converter chamber through the passages 4, forcing the metal from said passages down to the level of the bottom surfaces 10 of the end portions of the top wall, the metal rising to a higher level in the well 9 and opening, 3 as a result of this displacement. The blasts of air entering the converter chamber through the passages 4 thence flow through the body of metal, down into which the air is deflected by the baffles, thus causing the burning out of the impurities in the metal, which impurities discharge in gaseous form through the outlet 3. By this method of and means for introducing the air, a thorough bessemerization of the metal is effected, enabling twyers to be dispensed with, while at the same time permitting a magnesite-brick or other non-corrodible lining to be efficiently used, thus overcoming the disadvantages of and objections to the prior constructions hereinbefore mentioned. As a result, less labor and repairs are required in operating and keeping the converter in working condition, with economy in cost of operation and maintenance.

I claim:

1. A metallurgic converter comprising a cylindrical shell rotatably sustained, said shell having an air inlet at its top, an outlet at its top for the generated gases, and an inner non-corrodible lining extending on a generally inclined plane between said inlet and outlet and stepped to form a baffle surface to direct the air downward through the body of metal.

2. A metallurgic converter comprising a cylindrical shell rotatably sustained, said shell being provided with a non-corrodible lining and having at its top an air inlet and a gas outlet, the upper wall of the lining being arranged to form a contracted space communicating with the body of the shell and a well leading from the air inlet down into said space, and said upper wall being

provided with a baffled roof of stepped formation between said contracted space and the gas outlet.

3. A metallurgic converter comprising a cylindrical shell rotatably sustained and having an inner non-corrodible lining, an air inlet at the top of each end of the shell, and a gas outlet at the top of the center of the shell, the said lining being constructed to provide contracted spaces at the ends of the converter chamber, wells leading downwardly from the air inlets to said contracted spaces, and baffles between the respective contracted spaces and the central gas outlet.

4. A metallurgic converter having an air inlet with a well or passage leading therefrom down into the converter chamber below the normal level of the metal in said well and chamber, an outlet for the generated gases above the plane of the lower end of said well or passage, and a stepped baffle surface between said well or passage and said gas outlet.

5. A metallurgic converter having an air inlet with a well or passage leading therefrom down into the converter chamber below the normal level of the metal in said well and chamber, an outlet for the generated gases above the plane of the lower end of said well or passage, and a baffle surface extending on an inclined plane between said well or passage and said gas outlet, said baffle surface being of stepped formation.

6. A metallurgic converter comprising a cylindrical shell rotatably sustained, said shell having an inner non-corrodible lining with a baffled roof, an air inlet at each end, and a gas outlet at the center, substantially as described.

7. A metallurgic converter comprising a cylindrical shell rotatably sustained, said shell having an inner lining with a baffled roof of stepped formation, an inlet at each end, and a gas outlet at the center.

8. A metallurgic converter comprising a shell rotatably sustained and having a non-corrodible lining forming a chamber contracted at each end, air inlets leading downward into the contracted ends of the chamber, a central gas outlet at the top of the chamber, and baffles between the contracted ends of the chamber and the gas outlet.

In testimony whereof I affix my signature in presence of two witnesses.

HOWARD B. JERNEE.
